UNITED STATES PATENT OFFICE

FRANK E. FOWLER, OF ATHENS, GEORGIA

BOTTLE FILLING MACHINE

Application filed August 23, 1930. Serial No. 477,384.

This invention relates to improvements in devices for filling bottles with carbonated beverages, the general object of the invention being to provide means for closing communication between the head of the apparatus and the bottle filling tube whenever desired, so that the valve stem, filling tube and other parts can be removed without removing the carbonated liquid from the filler head or the bottles from the machine.

In machines as now constructed, in order to change the filling tube or valve or do any other work on parts of the valve mechanism, it is necessary to remove the complete valve from the head of the filler as well as to remove the bottles from the machine and to do this, the carbonated water must be drained from the filler head. It requires quite a bit of time to remove bottles, drain filler head and remove the valve from the head. Also, it is not desirable to drain the cold carbonated water from the head of the filler, as it will allow the metal head to warm up several degrees and will raise the temperature of water in the head when the same is filled again. The raising of the temperature of the carbonated water in the head will cause a loss of gas volumes in the bottles being filled until the water gets back to normal or same temperature as before the water was drained from the head.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a fragmentary sectional view showing a part of the machine, with the invention in use.

Figure 2 is a section on line 2—2 of Figure 1.

Figure 3 is a sectional view showing how the valve stem is adjustably connected with the diaphragm member.

Figure 4 is a section on line 4—4 of Figure 3.

As shown in the drawings, I place an elongated casing 1 in the filler head 2 of the machine, this casing having one end in communication with the diaphragm chamber 3 and its other end being in communication with the valve filling tube 4. The casing encloses the upper part of the valve stem 6 and the connection 7 of the stem with the diaphragm assembly 5. The casing is provided with an inlet opening 8 so that the liquid in the head 2 can flow into the lower part of the casing and thus pass into the filling tube 4. The opening 8 is formed by a short horizontal extension 8' of the casing which is formed with a downwardly and outwardly sloping end which provides a seat for a valve plate 9 which is hingedly connected to a projection on the casing, as shown at 10, so that gravity holds the valve on the seat, thus closing the opening. A depending projection 11 is formed on the lower part of the valve plate and a short shaft 12 is rotatably arranged in a part of the lower part of the head and has an arm 13 on its upper end for engaging the projection 11 when the shaft is turned in a certain direction which acts to open the valve. An arm 14 is fastened to the lower end of the shaft and is located under the head and exteriorly thereof so that this arm is accessible to the operator and enables him to open and close the valve whenever desired. The upper end of the stem 6 is threaded in a bore formed in the connection 7 and said stem is provided with the oppositely arranged notches 15 which are adapted to be engaged by the spring latch 16 pivoted to the connection 7 and extending through a slot therein. Thus the stem is adjustably connected with the diaphragm assembly and the latch 16 holds the parts in adjusted position.

From the foregoing it will be seen that the liquid in the head 2 will flow through the opening 8 when the valve 9 is opened, into the lower part of the casing and from this casing, the liquid will pass down the filling tube 4 into the bottle. When it is desired to remove the tube 4, the stem 6 or any

other parts of the valve assembly, it is simply necessary to turn the shaft 12 by its arm 14 to move the arm 13 out of engagement with the projection 11, which will permit the valve 9 to close the opening 8, which prevents the liquid in the head from entering the casing. Then the parts can be easily removed and renewed or replaced, as desired. After the repairs have been made, the shaft 12 is turned in an opposite direction to cause the arm 13 to open the valve and then the machine can be started.

It is thought from the foregoing description that the advantages and novel features 15 of the invention will be readily apparent.

It is to be understood that changes may be made in the construction and in the combination and arrangement of the several parts, provided that such changes fall within the scope of the appended claims.

What I claim is:

1. In combination with a bottle filling machine having a filling head, of an elongated casing rising within the head and having a diaphragm chamber at its upper end and a liquid inlet at its lower end communicating with the head, a gravity closing valve for the inlet, a filling tube extended from the casing without the head and detachable therefrom, a valve for the tube, a diaphragm assembly in said chamber, a stem carrying the last named valve and detachably connected with the diaphragm assembly for removal through the tube, and manually actuated means adjacent to the tube and operable outside of the head for opening the last named valve.
2. In combination with a bottle filling machine having a filling head, of an elongated casing rising within the head and having a diaphragm chamber at its upper end and a liquid inlet at its lower end communicating with the head, a gravity closing valve for the inlet, a filling tube extended from the casing without the head and detachable therefrom, a valve for the tube, a diaphragm assembly in said chamber, a stem carrying the last named valve and detachably connected with the diaphragm assembly for removal through the tube, a pivot journaled at one side of the tube, an arm on the pivot and acting upon the last named valve for opening the same, and a handle carried by said pivot and operable outside of the head to permit the opening of the last named valve by the arm.

In testimony whereof I affix my signature.
FRANK E. FOWLER.
